United States Patent Office

Des. 185,790

Patented Aug. 4, 1959

185,790

FRONT PANEL FOR A MAILBOX

Tsugio Kubota, Mill Valley, Calif., assignor to Schlage Lock Company, a corporation

Application April 7, 1958, Serial No. 50,350

Term of patent 14 years

(Cl. D13—2)

FIG. 1

FIG. 2

FIG. 3

Fig. 1 is a perspective of a front panel for a mailbox showing my new design.

Fig. 2 is a front elevation of the panel of Fig. 1, and,

Fig. 3 is a vertical cross section of the panel as taken along lines 3—3 of Fig. 2.

I claim:

The ornamental design for a front panel for a mailbox as shown.
